Chas. H. McGurrin.

UNITED STATES PATENT OFFICE.

CHARLES H. McGURRIN, OF KALAMAZOO, MICHIGAN, ASSIGNOR OF ONE-HALF TO CHARLES M. STEPHENS, OF SAME PLACE.

COPY-HOLDER FOR TYPE-WRITERS.

SPECIFICATION forming part of Letters Patent No. 365,837, dated July 5, 1887.
Application filed April 8, 1887. Serial No. 234,133. (No model.)

To all whom it may concern:

Be it known that I, CHARLES H. McGURRIN, of Kalamazoo, in the county of Kalamazoo and State of Michigan, have invented certain new and useful Improvements in Copy-Holders for Type-Writers, of which the following is a specification, reference being had to accompanying drawings.

The object of my invention is to produce a copy-holder for a type-writer which shall hold the copy to be type-written in front of the operator, which shall be adapted to be detached and folded for packing and transportation, and which shall also be adapted to indicate to the operator when the bottom of the page is reached without his having to lift the carriage to ascertain the fact.

In the accompanying drawings, illustrating my improved copy-holder, Figure 1 is a front view of my copy-holder in position, as in use it would be, at the rear of a type-writer, with only that part of the base or frame of the machine shown to which the copy-holder is secured. Fig. 2 is a side view of the copy-holder, the dotted lines indicating by mere diagram the position of the feed-roiler for the paper and the paper itself, with its end projecting back against the stop or gage of the holder, as explained in detail below.

30 A indicates a base-plate or support provided with flanges B and set-screws C, or any other ordinary appliance adapting it to be attached firmly to the base or frame D of a type-writer or caligraph.

35 E indicates a hollow curb or stump secured to the base-plate A, and provided with a set-screw, F, by means of which the standard G may be secured in place. This standard G is provided with a bend at H, leaving a space 40 between the parts h k, into which the upper end of the paper after the printing is done upon it may project.

K indicates a sliding stop or gage of any suitable form and provided with a set-screw, L, which may be adjusted upon the part h of the standard in such a position that when the bottom line has been printed upon the paper the top end of the paper will impinge against the gage, and thus indicate to the operator 50 that the page is finished without his having to

lift the carriage, as is usual. Even without the gage the space left by the bend in the standard serves a useful purpose, because it gives room for the paper to enter it, so that the copy-holder can be near the machine without its standard being in the way of the paper as it is printed upon.

M indicates a tubular section of the standard, which fits over the part N, and is held in place by means of a set-screw, O.

P indicates a cross-piece secured in the tubular section M of the standard, which is provided at each end with collars Q, with screws R, and with thumb-nuts S, by means of which the folding copy-holder T may be detachably secured to the standard.

U indicates hinges by means of which the holder may be folded. This holder may be such as illustrated, or in any usual or desired form of light frame adapted for the purpose 70 of holding copy.

V indicates the clamp secured to the top of the holder by means of screw W, passing through a flange, W', of the standard or fixed part of the clamp.

X indicates the spring-actuated jaw of the clamp, the other jaw being formed by the top plate, Y, of the holder.

Z indicates a bottom support, shelf, or ledge for the paper copy, preferably in trough-like shape, as shown, and detachably secured by screws a to the holder-frame.

b indicates clamp-fingers of spring metal pivoted to the copy-support Z, and adapted to fold, when not in use, down into the trough of the support. These fingers bear by spring action against a cross-plate, c, of the holder, and serve, with the clamp at the top and the support at the bottom, to hold the copy firmly in place. The clamp and the shelf or support 90 may be detached for packing and transportation by removing the screws that hold them in place. The holder-frame may also be detached and folded flat by removing the thumb-nuts S. The cross-piece P and the tubular section 95 M of the standard may be removed by loosening the set-screw O. The standard may be detached from the base by loosening the set-screw F. Thus I provide a detachable holder for

copy for use in connection with type-writers 100

and caligraphs, which can readily be taken to pieces and packed in small space, which holds the copy in front of the operator, and which indicates to him when he has reached the bottom of his page.

5 I do not confine my invention to the exact forms of mechanical details set forth, as considerable variation may be made therein without departing from its substance and essential features.

10 As the construction of a type-writer or caligraph forms no part of my invention, I have only illustrated so much of such machine as to indicate the position and utility of my improved copy-holder, which is an attachment 15 for such machine adapted to be secured in place in rear of the machine, so as to be directly in front of the operator, and also so as to serve to indicate to him when the printing of his 20 page is completed.

What I claim to be new, and desire to secure by Letters Patent of the United States, is—

1. The combination, with a type-writer, of a standard, bent as described, and secured in a fixed position in rear of the machine, and a copy-holder supported by the standard, substantially as set forth.

2. A standard for a type-writer, bent, as at H, and provided with a stop or gage to indicate when a page is printed, substantially as set forth.

3. A folding copy-holder, T, provided with hinges U, and a copy-support, Z, substantially as set forth.

4. The combination, with a folding copy- 35 holder, T, having hinges H, and a copy-sup- port, Z, of the clamp V at its top, and the clamp-fingers b, substantially as set forth.

5. The combination, with a copy-holder, T, of a shelf, Z, and pivoted clamp-fingers b, 40 adapted to fold down upon the shelf, substan- tially as set forth.

6. The combination, with a hinged folding copy-holder, T, of a clamp, V, a shelf, Z, car- 45 rying pivoted folding clamp-fingers b, the shelf, clamp V, and the copy-holder being de- tachable by means of the screws, substantially as set forth.

7. The combination, with a detachable base- 50 plate or support, of a detachable bent standard provided with an adjustable gage, and a de- tachable section, M, carrying a fixed cross- piece, P, adapted to support a copy-holder, substantially as set forth.

In testimony whereof I have hereunto sub- 55 scribed my name.

CHARLES H. McGURRIN.
